UNITED STATES PATENT OFFICE.

BENJAMIN HIRSCHHORN, OF NEW YORK, N. Y., ASSIGNOR, BY MESNE ASSIGNMENTS,
TO MILLIE PATENT HOLDING CO. INC., OF NEW YORK, N. Y., A CORPORATION OF
NEW YORK.

TEA CARTRIDGE.

Application filed February 1, 1923. Serial No. 616,317.

To all whom it may concern:

Be it known that I, BENJAMIN HIRSCHHORN, a citizen of the United States, and resident of the city of New York, in the 5 county of Bronx and State of New York, have invented certain new and useful Improvements in Tea Cartridges, of which the following is a specification.

The present invention relates to improvements in tea cartridges for percolating or extracting the flavor from tea-leaves or coffee. The invention pertains more particularly to that type of cartridges, which is described in U. S. Letters Patent No. 1,310,796, granted 15 to me on July 22, 1919.

In this patent a cartridge is described, comprising a bag of textile fabric, having its mouth drawn into folds, the mouth of the bag being closed by a metal strip, in the 20 form of a ring, which engages and compresses the folds, in combination with a suspending string which is attached to said bag by said strip. In making these cartridges, obviously, first a bag must be formed on a 25 sewing machine from a piece of textile fabric.

The main object of the present invention is to form a tea cartridge from a piece of textile fabric without first producing a bag, 30 thereby greatly reducing the cost of manufacture.

With these and other objects in view, which will more fully appear as the nature of the invention is better understood, the 35 same consists in the combination, arrangement and construction of parts hereinafter described, pointed out in the appended claim and illustrated in the accompanying drawings, it being understood that many changes 40 may be made in the size and proportion of the several parts and details of construction within the scope of the appended claim, without departing from the spirit or sacrificing any of the advantages of the invention. 45

One of the many possible embodiments of the invention is illustrated in the accompanying drawings, in which:—

Figure 1 is a plan view of a piece of fabric, from which the container of the cartridge is formed; Fig. 2 is a perspective view 50 of the container before its mouth is closed;

and Fig. 3 is an elevation of a completed tea cartridge, constructed in accordance with the present invention.

In producing the cartridge, first a piece 55 of open-mesh textile fabric, preferably of square or quadrangular configuration, is cut from a strip, tea-leaves or coffee, sufficient for a single brewing, being placed centrally thereon, and the edges of the said fabric piece gathered together, as shown in Fig. 2 of the drawings, whereby a bag-like receptacle 11 is obtained, within which the tea-leaves or coffee are confined. The mouth of 60 the receptacle so formed is then closed, by applying thereto a metallic strip 12, that is shaped to assume the form of a ring, which 65 embraces the folded portion of the receptacle below its mouth, holding the folds 70 under compression, so as to prevent escaping of the contents. The strip must, obviously, be made of non-corroding metal or of a metal that is properly prepared to prevent corrosion. For the purpose of facilitating the handling of the cartridge, there 75 is fixed thereto a flexible means, such as a string 13, to which is attached at its free end a handle 14, for instance of cardboard. This string serves also as the means for suspending the cartridge from the receptacle, such as a tea-pot or coffee-pot, in which the extraction is to take place. The string is secured to the cartridge by placing it against the folded mouth portion of the receptacle 80 85 11 before the strip 12 is formed.

From the foregoing it appears that the receptacle 11 is seamless, and that the ring-shaped closure strip 12 constitutes the means which holds the gathered edge portions of 90 the fabric piece under compression, to form a receptacle therefrom.

In brewing tea or coffee with the improved device, the cartridge is taken hold of by its handle 14 and lowered into a pot, the 95 free end of the string and handle being permitted to hang over the mouth of the pot, after which its cover is put in place. The cover thus holds the outer end of the string and handle ready for further operation. Into the pot is poured a suitable quantity of 100 boiling water, either before or after the insertion of the cartridge. When sufficient essence has been extracted from the tea-leaves

or coffee within the cartridge, the pot cover is removed and the bag withdrawn by grasping its handle 14.

What I claim is:—

- 5 A device for extracting essence from tea-leaves or coffee, comprising a piece of textile fabric having its edges gathered together so as to form a seamless receptacle,

and a metal strip engaging and compressing the mouth portion of the receptacle so formed so as to close the same.

Signed at New York, in the county of New York and State of New York, this 23rd day of February, A. D. 1922.

BENJAMIN HIRSCHHORN.
